UNITED STATES PATENT OFFICE

135,003

DESIGN FOR A COMBINATION DESSERT AND CAKE DISH

Ruby Sullivan, Cincinnati, Ohio

Application April 7, 1942, Serial No. 106,487

Term of patent 14 years

To all whom it may concern:

Be it known that I, Ruby Sullivan, a citizen of the United States, residing at Cincinnati, Hamilton County, and State of Ohio, have invented a new, original, and ornamental Design for a Combination Dessert and Cake Dish, of which the following is a specification, reference being had to the accompanying drawing, forming part thereof.

I claim:

The ornamental design for a combination dessert and cake dish, as shown.

RUBY SULLIVAN.
